JUICER

Herbert A. Wormeck and Frederick P. Hess,
Philadelphia, Pa., assignors to The Enterprise
Manufacturing Company of Pennsylvania,
Philadelphia, Pa., a corporation of Pennsyl-
vania

Application February 25, 1946, Serial No. 649,902

5 Claims. (Cl. 100—48)

1

This invention relates to a juicer and more particularly to the production of that type of juicer in which juices are expressed from the pulp of fruit or the like by means of a worm of the general type utilized in food choppers.

An important object of the invention is the provision in a structure of this character of an arrangement such that the principal operating elements, the worm, the strainer tube through which expressed juices are passed, and the hopper through which the material being juiced is delivered to the worm, are so constructed that they may be very rapidly disassembled for cleaning purposes.

Another object of the invention is the provision of a simple method of securing the strainer tube of the juicer in position with relation to the hopper while, at the same time, maintaining a maximum drainage area of the tube in exposed position for straining the juices expressed from the pulp.

Still another object of the invention is the provision in a structure of this character of a simple arrangement whereby the passage of the expressed juice from the strainer or hopper to the bearing of the worm may be avoided.

These and other objects we attain from the construction shown in the accompanying drawing wherein:

Fig. 1 is a longitudinal sectional view through a juicer constructed in accordance with our invention;

Fig. 2 is a section on line 2—2 of Fig. 1; and

Fig. 3 is a section on line 3—3 of Fig. 1.

Referring now more particularly to the drawings, the numeral 10 designates a vertically extending tube which may either comprise the feed hopper of the apparatus or a neck by which a tray type feed hopper may be positioned as suggested by the construction lines of Fig. 1. This tube, at its lower end, is provided with stirrups 11 and 12 which are formed in part by the lower end of the tube and in part by integral strap sections depending therefrom. These stirrups are circular in form and of differing diameters having tapering inner surfaces 13 for coaction with the tapered wall of strainer tube 14.

Strainer tube 14 consists of a conical tube of perforated sheet metal, this tube being produced by rolling a properly formed perforated sheet to produce the cone and securing the edges thereof along the major portion of the length of the tube by a retainer 15 forming a rib on this portion of the tube. This rib extends from the outer smaller end of the tube to the outer edge of an

2

opening 16 formed in the tube corresponding in size to the opening of the hopper tube 10. The rear, or larger end of the tube, has secured thereto an annular angle flange element 17, the projecting flange 18 of which is adapted to seat against shoulder 19 upon the outer face of the stirrup 12 and be clamped thereagainst by engagement with the stirrup 12 with bearing element 20. Bearing element 20 receives the shaft 21 of worm 22 which worm is of the type wherein the groove between the worm flange decreases in diameter as it approaches the worm end, the larger groove area being arranged in alignment with the hopper tube 10 and the opening 16 of the strainer. This worm internally fits the strainer and causes material, delivered to the hopper, to be progressed to the discharge mouth 23 of the strainer tube under increasing pressure in order that all available juices in the material may be expressed from the pulp and discharged through the strainer proper on the arrival of the pulp at the discharge 23. Obviously, in a structure of this character considerable strain is placed upon the outer end of the strainer tube due to frictional engagement of the pulp with the interior of the strainer wall and this strain would ordinarily serve to distort the strainer tube particularly since this tube is weakened by a formation of the opening 16. To prevent this distortion, the stirrup 11 has formed in the wall thereof a notch 24 receiving and fitting rib 15 of the strainer tube.

Another difficulty met with in juicers, particularly where the juicer is connected with drive mechanism of a type needing lubrication is a tendency of the lubricant to pass to the strainer chamber and a tendency of the expressed juices to move back to lubricated surfaces such as that of shaft 21. To insure against either contamination of the expressed juices or of the lubricant, the bearing 21 is formed with a forwardly projecting flange 25 between the forward edge of which and the stirrup 12, the ring flange 19 is axially clamped and the worm 22 is provided with an annular flange 26 fitting in the strainer 14 in the stirrup 12. This flange 26 is spaced from the adjacent end of bearing 20 to form a chamber 27 provided with an outlet 28, at present illustrated as formed partially in flange 25 and partially in the stirrup 12. Furthermore, shaft 21 is provided with an annular flange 29 which abuts the inner end of bearing 20. It will be obvious that the thrust of worm 22, in expressing pulp to outlet 23, will maintain the flange 29 in firm engagement with the end of bearing 20,

thus sealing to the greatest possible extent against the passage of oil from bearing 20. It will also be obvious that any pressure which may exist in the expressed juices by passing the worm flange 26 to chamber 27 will be immediately relieved and these juices may escape through the outlet 28.

To effect an assembly of this unit, other than its assembly with drive unit D, indicated in Fig. 1 the strainer tube may be slid into the stirrups 11 and 12 until the flange 18 engages the shoulder 19 and the worm 22 and its bearing placed in position and clamped by means of screws 30. The structure is thus capable of rapid assembly and disassembly and the separation of the various elements thereof for cleansing requires but a moment's time.

Since the construction herein illustrated is capable of considerable modification without departing from the spirit of our invention, we do not wish to be understood as limiting ourselves thereto except as hereinafter claimed.

We claim:

1. In a juicer, a feed hopper having an open bottom and provided with annular stirrups arranged at opposite sides of said open bottom, a strainer tube directed through and fitting within said stirrups and having a flange at one end, one of said stirrups having an external shoulder against which said flange abuts, a worm in said tube, and a bearing for the worm engaged with said stirrup to clamp the tube flange therebetween.

2. In a juicer, a feed hopper having an open bottom and provided with annular stirrups arranged at opposite sides of said open bottom, a strainer tube mounted in said stirrups and having one end thereof clamped to the outer face of one of said stirrups, said strainer tube having an opening for alignment with the hopper bore and beyond said opening from the clamped end thereof having a rib engaging in a notch in the other of the stirrups.

3. In a juicer, a feed hopper having an open bottom and provided with annular stirrups arranged at opposite sides of said open bottom, a strainer tube directed through and fitting within said stirrups and having a flange at one end, one of said stirrups having an external shoulder

against which said flange abuts, a worm in said tube, a bearing for the worm engaged with said stirrup to clamp the tube flange therebetween, said strainer tube having an opening for alignment with the hopper bore and beyond said opening from the clamped end thereof having a rib engaging in a notch in the other of the stirrups.

4. In a juicer, a feed hopper having an open bottom and provided with annular stirrups arranged at opposite sides of said open bottom, a strainer tube directed through and fitting within said stirrups and having a flange at one end, one of said stirrups having an external shoulder against which said flange abuts, a worm in said tube, a shaft for said worm, a bearing for the worm shaft having an annular axially directed flange engaged with said stirrup to clamp the tube flange therebetween, an annular radial flange on the worm shaft engaging the outer end of the bearing, a flange on the inner end of the strainer tube, the bearing, its axial flange, said one stirrup and the worm flange forming an annular chamber containing the radial flange of the worm shaft and having a drainage outlet.

5. In a juicer, a feed hopper having an open bottom and provided with annular stirrups arranged at opposite sides of said open bottom, said stirrups being of different diameters, a tapered strainer tube mounted in said stirrups and having the larger end thereof clamped to the outer face of the larger of said stirrups, said strainer tube having an opening for alignment with the hopper bore and beyond said opening from the clamped end thereof having a rib engaging in a notch in the smaller of the stirrups.
